Inventor

Jay P. Nissen

United States Patent Office.

INGWER P. NISSEN, OF DAVENPORT, IOWA.

Letters Patent No. 66,731, dated July 16, 1867; antedated March 12, 1867.

IMPROVED WASHING MACHINE.

The Schedule referred to in these Letters Patent and making part of the same.

TO ALL WHOM IT MAY CONCERN:

Be it known that I, INGWER P. NISSEN, of Davenport, in the county of Scott, and State of Iowa, have invented a new and improved Washing Machine; and I do hereby declare that the following is a full and exact description thereof, reference being had to accompanying drawings, making a part of this specification, in which—

Figure 1 is a perspective view.

Figure 2 is the outside view of half circle washing-box separated from the standard, while

Figure 3 is an inside view of the washing-box.

Letter A represents the standard framed together in the ordinary manner of framing by mortising with a groove at the top of each upright piece for receiving the axle attached to washing-box. Letter B represents the sides of the washing-box, which are of wood. Letter C represents the bottom of the washing-box, which is of zinc attached to the sides B by being placed into a groove running around the inside circle of the sides B about one-fourth of an inch from the bottom edge of sides B. Letter D represents the cross-braces securely attached to the bottom of side pieces B, so as to rest in upon the bottom of zinc C. Letter E represents the cross-brace upon the bottom of wash-box, into which is a hole with wooden plug for the purpose of passing out the water when not required in the wash-box. Letter F represents a flat piece of wood or strip securely fastened from top to bottom on outside centre of each side piece of wash-box marked B. Letter O represents the iron pin securely fastened into each of the strips F, and projecting out so as to form the axle, which holds the washing-box, fig. 2, upon the standard, fig. 1. Letter G represents the top of the wash-box, fig. 2. Letter H represents the lid upon the top of wash-box, fig. 2, which is held to its place by wooden buttons marked letter I. Letter J represents the handles of wood or iron upon each end of top of wash-box, fig. 2, while letter K represents the strips upon the inside of wash-box, which strips are triangular-shaped, and are securely fastened directly opposite the outside strips or braces marked D.

What I claim for my invention, and desire to secure by Letters Patent, is—

The combination of the sides B, the zinc bottom C, with the braces D and triangular ribs K, when the same is pivoted and hung upon the standards A, as and for the purpose specified.

INGWER PETER NISSEN.
